Earl L. Simpson

BY

William W. Barnes, ATTORNEY

UNITED STATES PATENT OFFICE.

EARL L. SIMPSON, OF BALTIMORE, MARYLAND, ASSIGNOR TO SAID SIMPSON AND JAMES P. FUNK, TRUSTEES, OF BALTIMORE, MARYLAND.

TONE MODIFIER OR SHARPENER FOR DRUMS.

Application filed September 22, 1924. Serial No. 739,166.

To all whom it may concern:

Be it known that I, EARL L. SIMPSON, a citizen of the United States, a resident of Baltimore city, in the State of Maryland, have invented a new and useful Tone Modifier or Sharpener for Drums, of which the following is a specification.

The object of my invention is the providing of a tone-sharpener for drums which may 10 be easily applied and adjusted.

A further object of my invention is the providing of means of attaching a tone-sharpener for drums on the exterior of the same.

15 A further object of my invention is the providing of means of adjustably securing a tone-sharpener to a drum.

20 A further object of my invention is the providing of an improved material to be used in a tone-sharpener for drums.

A further object of my invention is the 25 providing of improved means of adjusting a tone sharpener on drums.

With the foregoing and other objects in view, my invention consists of the novel construction, combination and arrangement of parts as herein-after specifically described and illustrated in the accompanying drawings, wherein is shown the preferred embodiment of my invention.

30 In the drawings of the herein-described embodiment of my invention, Fig. 1 is a view of a bass-drum, partially in section, upon which my tone sharpener is adjustably and detachably secured. Fig. 2 is a view taken at right angles to that shown in Fig. 1. Fig. 3 is an enlarged view of the tone sharpener showing partially the method of attaching the mountings to the same; and 35 Fig. 4 is an enlarged view partially in section of the arm adjusting means.

Similar numerals refer to similar parts throughout the several views.

1 is the shell of the drum. 2 are the heads. 45 3 are the rims. 4 is the rim clamp, which is provided with extensions 5 on the inside and 6 on the outside between which extension rim 3 is clamped. The clamping means consists, in the case illustrated, of a screw

7 provided with a head 8 and pressing 50 against compressor plate 9.

On rim clamp 4 is lug 10 through which locking-bolt 11 passes and carries the same. Locking-bolt 11 is provided with locking-nut 12 and operates in locking- 55 sleeve 13.

In locking-bolt 11 is a hole 14; in locking-sleeve 13 is hole 15. 16 is the arm which in this case consists of a circular rod neatly fitting through holes 14 and 15, and carries 60 on its end an enlarged portion 17 through which screw 18 operates.

Screw 18 is provided with head 19 and is flexibly or adjustably secured in socket 20 to permit a slight angular variation of said 65 socket. Socket 20 is secured to tone sharpener body 21. Over the face of tone sharpener 21 is secured felt 22 of some considerable thickness, which acts as the tone sharpener. 70

The operation of my invention is as follows: Clamp 4 is secured to the rim of the drum and may be used on either head, some musicians preferring it on the beater head and some on the other head. Arm 16 is ad- 75 justed to position the tone sharpener on the head as desired by the musician, or according to the size and character of the drum operated upon, and is carried by the locking bolt 11 and is secured thereto in any desired 80 position by means of the locking-nut 12 and locking-sleeve 13. This securing may be in any position and provides a means of removing the tone sharpener from the head of the drum or adjusting the pressure on the 85 same, as desired, as bolt 11 may be rotated in lug 10.

As a further adjustment, screw 18 is provided to adjust relatively the tone sharpener body 21 and arm 16. 90

Having thus described my invention, what I claim and desire to secure by Letters Patent is:

1. A tone modifier for drums comprising, a body provided with means for detachably 95 securing the same to the exterior of a drum by clamping the rim thereof and adjustable means whereby the said body may contact at

a pre-determined point on a head of said drum, and means of maintaining positive sustained contact between said body and said head.

5. 2. A tone modifier for drums comprising, a body provided with means for maintaining the same at a predetermined point on the

exterior surface of a drum head, means for regulating the pressure of said body against said drum head, and means for wabbly 10 mounting said body whereby the said body may adjust itself into the plane of the drum-head.

EARL L. SIMPSON.
